[57] CLAIM

The ornamental design for a combined index tab and paper holder, as shown and described.

DESCRIPTION

FIG. 1 is a top perspective view of a combined index tab and paper holder showing my new design, it being understood that the undisclosed bottom perspective view is the same as shown in FIG. 3 except for the angled interior clip; FIG. 2 is a side elevational view thereof, the undisclosed side being a mirror image;

FIG. 3 is a bottom perspective view of a second embodiment of FIG. 1;

FIG. 4 is a top perspective view thereof; and,

FIG. 5 is a side elevational view thereof, the undisclosed side being a mirror image.
